His Attorney.

UNITED STATES PATENT OFFICE.

LEWIS HALL, OF WORTH, WOODFORD COUNTY, ILLINOIS.

HARVESTER-REEL.

SPECIFICATION forming part of Letters Patent No. 338,957, dated March 30, 1886.

Application filed February 9, 1885. Serial No. 155,370. (No model.)

To all whom it may concern:

Be it known that I, LEWIS HALL, of Worth township, in the county of Woodford, in the State of Illinois, have invented an Improved 5 Harvester-Reel; and I do hereby declare that the following is a full, clear, and exact description thereof, reference being had to the annexed drawings, making a part of this specification, in which like letters of reference 10 refer to like parts, and in which—

Figure 1 represents a perspective view of a harvester-platform, showing the invention; and Fig. 2, a side elevation of my invention, showing also the path of the reel-bat.

15 This invention relates to reels for throwing the grain over against the sickle and upon the platform in reapers or harvesters.

20 My device consists, essentially, of a single reel-bat supported from and given the required motion by vibratory reciprocating bars.

The means for operating the bars consists of a shaft having cranks giving a circular motion to the ends of the bars opposite to the reel-bat, and sliding supports for the bars.

25 In the drawings, P is the platform of a reaper or harvester, S the sickle at the front edge of the platform, and B the reel-bat secured to the oscillatory arms C. Said reel-bat arms are supported from the front ends of the vibratory bars A, whose rear ends are attached to the cranks H' of the shaft H. To pivotally support the bars A, and at the same time permit their reciprocating movement, I provide the sleeves G, which are adapted to slide along the guide-rods F, and are pivoted to the collars G' on the bars A. By changing the positions of the collars G' toward one end or the other of each bar A the leverage of said bars is changed and the vertical play of the reel-bat B increased or diminished in proportion 35 to the distance of said collars from the ends of the bars A. A set-screw or other fastening, G², secures each collar G' at the desired place.

If the reel-bat B is fastened directly to the 40 ends of the bars A, the horizontal movement thereof is only equal to the length of the stroke of the cranks H'. To secure a sufficient movement of the reel-bat thus operated, the said cranks must be quite long and the bars must 45 move as far and fast as the reel-bat. This

construction is therefore open to the objection that the required motion of said bars may shake and jar the reaper. The path of the reel-bat will also be oval. To render such path approximately rectilinear, or so at least 55 when the reel-bat is approaching the sickle and platform and rising therefrom, and also to decrease greatly the stroke of the bars with the same horizontal play of the reel-bat, I have devised the following construction: The reel-bat B, instead of being secured to the ends of the bars A, is fastened to the ends of the oscillating arms C. These arms are pivoted to the ends of said bars, and thus means are provided to oscillate them forward when said bars 60 advance, and to swing them backward when the bars retreat. This will then considerably increase the horizontal movement of the reel-bat and somewhat modify its vertical play. For thus oscillating the arms C relative to the bars 65 A, the means which I have adopted consists of a simple connecting-rod, D, joining the prolonged upper end of each arm C to the guide-rod F. Now, as the bars A move in a horizontal direction, the upper ends of the 70 arms C being held by said connecting-rods, the lower ends of said arms, and therefore the reel-bat, are moved a greater distance. By changing the pivotal points of these arms and connecting-rods variations in the path and the 75 throw of the reel-bat can be made.

As shown in Fig. 2, my oscillating arm-connection of the reel-bat to the vibratory reciprocating bars gives the desired rectilinear path to the stroke of the reel-bat.

80 The desirability of the rectilinear path of the reel-bat lies in the fact that it enables the said reel-bat to pass straight down in front of the grain without beating any down, and to sweep the grain to the sickle and onto the platform, and to rise up therefrom without carrying any of the grain up with it.

To revolve the shaft H, and thereby give the required motion to the reel-bat mechanism, I usually mount a bevel-gear, K, on said shaft, 85 and have said gear mesh with one on some shaft of the reaper or harvester. In some machines a sprocket-wheel and chain might be more advantageous. The bearing-brackets J of said shaft I make vertically adjustable by 90 95 100

having the stems J' in two parts, held together by bolts passing through slots therein. The position of the center of motion of the reel-bat B is varied by this adjustment of the bearings 5 J. I prefer to have the stems J' curved, as shown in Fig. 2.

To adapt the reel-bat for either high or low grain by so adjusting it as to make its working path high up from the ground or low down, 10 almost, if not quite, touching the ground, I have devised the following means: The rear ends of the guide-rods F are pivoted or hinged to the rear edge of the platform P, and their front ends are provided with means for vertical adjustment. To secure both rods F rigidly together, so as to enable the adjustment of one to similarly affect the other, I fasten the rear portion of each to the tail-board P', as shown in Fig. 1. From the front end of one guide-rod 15 F extends the connecting-rod M to the crank-arm N of the rock-shaft N'. By oscillating said crank-arm toward or from the guide-rods the end of the latter is raised or lowered accordingly. For operating the crank-arm N 20 I provide the hand-lever L, connected to the rock-shaft N'. The said lever is held at any desired inclination by the segmental rack L', fixed to the rock-shaft bearings, and the bolt L², engaging with the teeth of the said rack and 25 operated by the hand-piece L³. Said lever L is prolonged downward, and is provided with a stirrup at its lower end, to enable the same to be controlled by the foot of the driver.

What I claim as my invention, and for which 30 I desire Letters Patent, is as follows, to wit:

1. In a harvester, the combination of the reel-bat, the arms to which said bat is secured, and the vibratory bars supporting and operating said reel-bat arms, whereby the grain is 35 delivered to the sickle and upon the platform, substantially as described.

2. In a harvester, the combination of the reel-bat, its supporting-arms, vibrating bars supporting said arms, sliding pivots supporting said bars, and cranks for operating said bars, substantially as and for the purpose set forth.

3. The combination of the reel-bat, the supporting vibratory bars, the operating-cranks, 40 the sliding supporting-pivots, and means, substantially as described, for adjusting said pivots along said vibratory bars, whereby the vertical movement of the reel-bat may be varied, substantially as and for the purpose set forth.

4. The combination of the reel-bat, the oscillating arms to which it is secured, and the vibratory supporting and operating bars, pivoted at their ends to said arms in such a manner that the movement of said bars shall move 45 said arms in the same direction, substantially as and for the purpose described.

5. The combination of the reel-bat, its oscillatory supporting-arms, the vibratory operating-bars, and the rods connecting the upper

ends of said oscillatory arms to fixed points, substantially as and for the purpose specified.

6. The combination, with the reel-bat and vibratory bars supporting the same, of the shaft and cranks operating said bars, the 70 guide-rods, and sleeves pivoted to said bars and adapted to slide along said guide-rods, substantially as and for the purpose specified.

7. The combination of the reel-bat, the vibratory bars supporting the same, the shaft 75 and cranks operating said bars, the guide-rods, the collars adjustable along said bars, and sleeves swiveled to said collars and adapted to slide along said guide-rods, as and for the purpose described. 80

8. The combination of the reel-bat, the vibratory bars supporting the same, the shaft and cranks operating said bars, the guide-rods hinged at their rear ends to the rear edge of the platform, mechanism for raising 85 and lowering the free ends of said guide-rods, and sleeves sliding on said rods and pivoted to said bars, substantially as and for the purpose set forth.

9. The combination of the vibratory bars, 90 the operating shaft and cranks, the guide-rods, the sliding sleeves pivoted to said bars, the oscillating arms pivoted at intermediate points to the ends of said bars, the reel-bat fastened to the lower ends of said oscillating arms, and connecting-rods joining the upper ends of said oscillating arms to the guide-rods, substantially as and for the purpose set forth. 95

10. The combination of the vibratory bars, 100 the operating shaft and cranks, the guide-rods pivotally held at their rear ends to the rear edge of the platform, mechanism, substantially as described, for adjusting the height of said guide-rods, the sliding sleeves 105 pivoted to said vibratory bars, the oscillating arms pivoted at intermediate points to the free ends of said vibratory bars, the reel-bat secured to the lower ends of said oscillatory arms, and connecting-rods joining the upper 110 ends of said oscillatory arms to the guide-rods, as set forth.

11. The combination of the reel-bat, the vibratory bars supporting the same, intermediate sliding pivots for said bars, the shaft and 115 cranks operating the vibratory bars, and the adjustable brackets J, substantially as specified.

12. In combination with the platform P of a harvester, the shaft H, having the cranks H', 120 the brackets J, holding said shaft to the rear edge of said platform, the vibratory bars A, held at their rear ends to said cranks, the guide-rods F, hinged to the rear edge of the platform, the tail-board P', fastened rigidly to 125 said guide-rods, the collars G', adjustable upon said bars A, the sleeves G, swiveled to said collars and adapted to slide along said guide-rods, the oscillating arms C, pivoted at intermediate points to the ends of the bars A, 130

the reel-bat B, secured to the lower ends of the arms C, the connecting-rods D, joining the upper ends of said arms C to the ends of the guide-rods F, the rock-shaft N', the crank-arm N, the rod M, joining said crank-arm N to the end of one of the guide-rods, the lever L, the segment-rack L', the bolt L², engaging with said rack, and the hand-piece L³, as herein described.

In testimony that I claim the foregoing invention I have hereunto set my hand this 31st day of January, 1885.

LEWIS HALL.
